US0D1019318S

(12) **United States Design Patent** (10) **Patent No.:** **US D1,019,318 S**
(45) **Date of Patent:** **** Mar. 26, 2024**

(54) **SCISSOR**

(71) Applicant: **Shenzhen Jiazhida Electronic Commerce Co., Ltd.**, Shenzhen (CN)

(72) Inventor: **Zonghua Wu**, Shenzhen (CN)

(73) Assignee: **Shenzhen Jiazhida Electronic Commerce Co., Ltd.**, Shenzhen (CN)

(**) Term: **15 Years**

(21) Appl. No.: **29/859,155**

(22) Filed: **Nov. 8, 2022**

(51) **LOC (14) Cl.** **08-03**

(52) **U.S. Cl.**

USPC **D8/57**

(58) **Field of Classification Search**
